UNITED STATES PATENT OFFICE.

EDWARD KRONMAN, OF BROOKLYN, NEW YORK.

COMBINED STERILIZING AND WATER-HEATING APPARATUS.

1,004,036.

Specification of Letters Patent. Patented Sept. 26, 1911.

Application filed August 20, 1910. Serial No. 578,222.

To all whom it may concern:

Be it known that I, EDWARD KRONMAN, a citizen of the United States, residing in Brooklyn, Kings county, and State of New York, have invented certain new and useful Improvements in Combined Sterilizing and Water-Heating Apparatus, of which the following is such a full, clear, and exact description as will enable any one skilled in the art to which it appertains to make and use the same, reference being had to the accompanying drawings, forming part of this specification.

In some municipalities the authorities have prohibited barbers from using hot water that is prepared by heating standing or still water and require that the hot water used in this trade shall in some way be connected with a running water supply or main.

By my present invention I provide simple and economical means for obtaining a running supply of hot water, which may be readily drawn off for use as desired, and which device is operatively combined with a sterilizer.

I have illustrated types of my invention in the accompanying drawings, wherein:—

Figure 1 is a front view of my improved apparatus shown as connected with an ordinary wash stand. Fig. 2 is an enlarged view in central vertical section of the steam-compartment and water-heater and heating means, shown as detached. Fig. 3 is an under side view of the steam-compartment and the part of the water-heater or coil lying beneath the same. Fig. 4 is a cross-sectional view of the part of the water-heater or boiler lying within the steam-compartment and shown as detached. Fig. 5 is a central vertical sectional view of the steam compartment with a modified form of water heater within the same. Fig. 6 is a detail view of the T-pipe fitting. Fig. 7 is a central vertical sectional view of the steam compartment with a modified form of water heater.

Referring to the drawings, in which like numbers of reference designate like parts throughout, 1 indicates a sterilizing compartment having the doors 2 and 3 at the respective ends thereof for the introduction and withdrawal of the articles to be sterilized, such as towels, for example. This sterilizing compartment is in communication with the subjacent steam-compartment or drum 4, and all of which parts are con-

structed and operated substantially like the corresponding parts of the apparatus set forth in my U. S. Patent No. 883,463, granted March 31, 1908, and to which reference may be had in regard to said parts. In this form of sterilizer, the water, indicated at 5, is placed in the steam compartment 4, and heat applied to generate steam which passes upwardly into the sterilizing chamber 1, as set forth in said patent, but as the water 5 is still water its use as hot water for shaving or shampooing purposes in barber shops is prohibited. In my improved apparatus, I combine with this sterilizer a water heater having a running water supply and which fully complies with all sanitary requirements. Beneath the steam compartment or drum 4, I place a metallic pipe-coil 6, which is connected with a running water supply pipe or city main 7, and also with a pipe connection 8, which runs to the ordinary wash basin 9, where it is provided with a drawing off faucet 10, which is operated by hand in the usual way whenever it is desired to draw a quantity of hot water for the usual purposes for which it is used in a barber shop.

Within the steam compartment 4, is a closed receptacle or boiler 11, which is provided with an inlet and outlet connection 12 and 13, respectively, with the pipe coil 6. The fitting 14, which unites the supply pipe 7, pipe coil 6, and boiler inlet 12, and likewise the fitting 15, which connects the boiler outlet 13, the pipe coil 6, and the drawing off pipe connection 8, being T-shaped so that the water may flow from one connected part to the other and thus the water may flow through the heating coil and thence out of drawing off pipe 8, or it may pass through said coil thence into the boiler or part 11, and from there to the drawing off pipe 8. In either case, running hot water is supplied to the drawing off pipe 8. An ordinary gas-burner 16, is placed beneath the steam-compartment or drum 4 and the pipe-coil 6 in order to give a high direct heat to both of said parts and thereby heat or boil the water in each. In addition to the boiler 11, being supplied with boiling water from the pipe coil 6, the contents 17 of the boiler are also heated by the highly heated still water 5, in the steam compartment, in which said boiler is submerged. When the temperature of the water 5 is below that in the boiler, the heat of the latter will raise the temper-

ature of the surrounding water 5, and so there is a mutual action between the boiler and the steam-compartment in this respect.

In Figs. 2 and 4, the boiler or storage re-
5 ceptacle 11, is a horizontal cylinder with the closed ends bowed outwardly.

In Fig. 5 I show the boiler in the form of a vertical cylinder 18, which provides an annular space of uniform width between
10 itself and the steam drum 4.

In Fig. 7, the inner vessel or boiler is shown in the form of a pipe-coil 19, instead of a cylinder, and this operates substantially in the manner hereinbefore described
15 in reference to the boiler 11.

The apparatus is mounted on a stand 20, at a place on the floor 22 conveniently near the washstand 9, at which place the running hot water is constantly supplied by the
20 heater which at the same time is combined with the sterilizer. This combined apparatus has the advantage of simplicity, compactness and comparative cheapness and it presents an attractive appearance and serves
25 to conceal the water heater, which is often-times very unsightly. The single burner 16, serves the double function of providing the necessary heat for the sterilizer and the water heater for the running water. When-
30 ever it is desired to empty the water 5, from the steam drum 4 for cleaning the drum, this may be done by means of the faucet 21, which is tapped into the lower end of the drum.

35 Having thus described my invention, what I claim and desire to secure by Letters Patent is:—

1. A combined sterilizer and water heater and hot water supply, comprising a sterilizing compartment, a steam generator communicating with said compartment and supplying steam thereto, a water heater beneath said generator and a water supply connected with said heater, a reservoir within said generator and connected with said water heater
40

and receiving the hot water therefrom, means for heating the water heater and generator, and a pipe connection and faucet for drawing off the hot water from said reservoir as desired, whereby the contents of said reservoir and said generator may impart their heat to each other.

2. A combined sterilizer and water heater and hot water supply, comprising a sterilizing compartment, a steam generator com-
55 municating with said compartment and sup-
plying steam thereto, a heating coil outside of said generator and a water-supply con-
nected therewith, a reservoir within said generator and connected with said heating
60 coil and receiving the hot water therefrom, a burner for heating said generator and heating coil simultaneously, and a pipe con-
nection and faucet for drawing off the hot
65 water from said reservoir as desired, where-
by the contents of said reservoir and gen-
erator may impart their heat to each other.

3. A combined sterilizer and water heater and hot water supply, comprising a sterilizing compartment, a steam generator com-
70 municating with said compartment and sup-
plying steam thereto, a heating coil beneath said generator and a water supply con-
nected therewith, a reservoir within said generator and having an inlet and an outlet
75 pipe, a drawing off pipe and faucet, the said water supply, inlet pipe and heating coil being connected by a three-way fitting and the said outlet pipe, pipe coil and drawing
off pipe being likewise connected by a three-
80 way fitting, and a burner for heating said generator and pipe coil, substantially as and for the purpose set forth.

In testimony whereof, I have hereunto set my hand in the presence of the two sub-
85 scribing witnesses.

EDWARD KRONMAN.
